United States Patent Office

Des. 201,177
Patented May 25, 1965

201,177

STRADDLE CARRIER

Marshall D. Sawdey and William A. Williamson, Battle Creek, Mich., assignors to Clark Equipment Company, a corporation of Michigan

Filed Dec. 24, 1964, Ser. No. 83,149

Term of patent 14 years

(Cl. D14—3)

FIG. 1

FIG. 2

Des. 201,177

PAGE 2

FIG. 3

FIG. 4

FIG. 5

FIGURE 1 is a front perspective view of a straddle carrier embodying our new design;

FIGURE 2 is a rear perspective view thereof showing the side opposite that shown in FIG. 1;

FIGURE 3 is a side view thereof;

FIGURE 4 is a front view thereof; and

FIGURE 5 is a top perspective view thereof.

The dominant features of our design reside in the portions illustrated in solid lines.

We claim:

The ornamental design for a straddle carrier, as shown and described.
